(57) **CLAIM**

We claim the ornamental design for a central portion of a racquet, as shown and described.

DESCRIPTION

FIG. 1 is a front perspective view of a racquet including a central portion;

FIG. 2 is a front view of the racquet of FIG. 1;

FIG. 3 is a rear view of the racquet of FIG. 1;

FIG. 4 is a first side view of the racquet of FIG. 1;

FIG. 5 is a second side view of the racquet of FIG. 1.

FIG. 6 is a bottom view of the racquet of FIG. 1;

FIG. 7 is a top view of the racquet of FIG. 1;

FIG. 8 is a front view of the central portion of the racquet taken about line 8-8 of FIG. 2; and,

FIG. 9 is a front perspective view of the central portion of the racquet of FIG. 8.

The dashed lines shown in FIGS. 1 through 9 are included for the purpose of illustrating environmental elements only and form no part of the claimed design.

1 Claim, 7 Drawing Sheets
